ATTACHMENT FOR LOOMS

Walter L. Holt, La Grange, Ga., assignor of one-third to W. H. Young, Sr., Muscogee County, Ga.

Application April 19, 1937, Serial No. 137,852

4 Claims. (Cl. 139—337)

This invention relates to an attachment for looms of that type including an electrically operated warp stop motion, and has for its object to provide, in a manner as hereinafter set forth, a normally inactive attachment of the circuit closing type interposed in a circuit extended from the circuit for the electrically operated warp stop motion and made active by and on the falling of the loom harness when the straps which control the vertical movement of the harness break, thereby closing the warp stop motion circuit resulting in the discontinuance of the operation of the loom.

The invention aims to provide, in a manner as hereinafter set forth, means for automatically stopping the operation of a loom having an electrically operated warp stop motion when the loom harness falls thereby preventing what are known as pick-outs which result in what is known as seconds in the cloth while in the process of weaving.

Further objects of the invention are to provide, in a manner as hereinafter set forth, a loom attachment for the purpose referred to which is simple in its construction and arrangement, strong, durable, compact, readily installed with respect to the loom, positive in its action, thoroughly efficient in its use, automatically made active from the loom harness, capable of being adjusted and comparatively inexpensive to manufacture.

To the above ends and to others which may hereinafter appear, the invention consists of the novel construction, combination and arrangement of parts as will be more specifically referred to and illustrated in the accompanying drawings wherein is shown an embodiment of the invention, but it is to be understood that changes, variations and modifications may be resorted to which fall within the scope of the invention as claimed.

In the drawings:

Figure 1 is a fragmentary view in front elevation of a loom showing the adaptation therewith of the attachment in accordance with this invention.

Figure 2 is a fragmentary view in side elevation of a loom showing the adaptation therewith of the attachment in accordance with this invention.

Figure 3 is a front elevation of one of the units of the attachment,

Figure 4 is a side elevation of the form of circuit closing structure employed in connection with each unit of the attachment, and

Figure 5 is a fragmentary section on line 5—5, Figure 3.

With reference to the drawings, 6 generally indicates a loom, 7 the loom harness, 8 the straps for controlling the vertical movement of the harness, 9 the drop eye bars, 10 the warp stop bars, 11, 12 a pair of frame parts and 13 the circuit for the electrically operated warp stop motion. The foregoing elements are of the well-known form and arrangement.

The attachment includes a normally open circuit 14 which leads off of the circuit 13 and a pair of oppositely disposed parallel spaced circuit closing units 15, 16 of like form to be more fully referred to and which have parts interposed in the circuit 14. The latter also includes a pair of conductors 17, 18, a pair of grounds 19, only one shown and the eye bars 9.

Each circuit closing unit includes an angle-shaped hanger member 20 formed of a vertically disposed rigid flat leg 21 and a horizontally disposed resilient leg 22 formed of a curved inner stretch 23 and an upwardly inclined flat outer stretch 24. The leg 21 is bifurcated, as at 24, and the furcation therein opens at the top edge 25 thereof. The stretch 24 is bifurcated as at 26 and the furcation therein opens at the free end thereof. The member 20 of the unit 15 has its leg 21 positioned against and secured to the frame part 11 by a headed holdfast means 27 extending through such frame part and the furcation in leg 21 of such member. The member 20 of the unit 16 has its leg 21 positioned against and secured to the frame part 12 by a headed holdfast means 28 extending through such frame part and the furcation in the leg 21 of such member. When the units are anchored to the frame parts 11, 12, the legs 22 of the members 20 extend towards each other. The furcations in the legs 21 permit of vertically adjusting the units 15, 16 relative to the frame parts 11, 12 respectively.

Each circuit closing unit includes a flat rectangular contact plate 29 and a resilient rectangular circuit closing member 30 arranged over, secured at its outer end to the outer end of and having its remaining portion spaced from the upper face of plate 29. The member 30 is formed in proximity to its inner end with an opening 31 into which extends the body of an annular flanged insulation member 32. The flange of 50 the latter is indicated at 33 and abuts the lower face of member 30. Seated on the upper face of member 30 is a washer 34 of insulation material. Extending through the member 32 and washer 34 is a contact 35 in the form of an in-

verted headed screw. Carried by the contact 35 is a clamping nut 36 for the member 32 and washer 33. Carried by the contact 35 above the nut 36 is a binder nut 37 for a conductor 17 or 5 18. A plate 29 is disposed transversely of the stretch 24 of a leg 22 and is anchored to such stretch by a headed bolt 38 countersunk in and extending through plate 29, the furcation in stretch 24 and depending below the latter, a 10 washer 39 on the shank of bolt 38 and a nut 40 bearing against the lower face of washer 39 and threadedly engaging with bolt 38. The latter in connection with the washer 39 and nut 40 coact to clamp plate 29 to stretch 24. The plate 29 15 is arranged at its transverse median on stretch 24 and is of a length to extend outwardly and inwardly with respect to the sides of the stretch 24. The furcation in the stretches 24 permit of the adjusting of the plates 29 lengthwise of said 20 stretches. The plates 29 and members 30 are substantially of the same length. The ends of the members 30 carrying the contacts 35 are normally spaced from plates 29 whereby the contacts 35 will be held normally free of engagement 25 with plates 29. The grounds 19 lead from the plates 29. The conductor 17 leads from one end of the drop eye bars 9 to the contact 35 of the unit. The circuit closing members 30 are positioned in the downward path of the harness 7 30 whereby when the straps 8 break and the harness 7 drops it will engage the members 30 and cause contacts 35 to engage plates 29 and close the circuit 14 whereby the operation of the loom will be discontinued. The arrangement of the 35 units 15, 16 in relation to the harness 7 is such that if one of the straps 8 breaks on one side of the harness 7, the latter will fall resulting in making active the unit 15 or 16 and closing circuit 14 whereby the operation of the loom will 40 be discontinued.

What I claim is:

1. In an attachment for the purpose set forth, a normally inactive circuit closing unit formed of an L-shaped supporting member having a vertical leg for anchoring to a support and a 45 horizontal leg extending at an angle from the lower end of the vertical leg, a contact plate disposed transversely of said horizontal leg, a depressible resilient circuit closing member arranged over and having one end anchored to one 50 end of said plate, a contact normally spaced from and for coaction with said plate when said member is depressed, said contact extending through said member at the other end of the latter, means for insulating said contact from said member, and means for securing said plate to the horizontal leg. 55

2. In an attachment for the purpose set forth, a normally inactive circuit closing unit formed of an L-shaped supporting member having a vertical leg for anchoring to a support and a horizontal leg extending at an angle from the lower end of the vertical leg, a contact plate disposed transversely of said horizontal leg, a depressible resilient circuit closing member arranged over and having one end anchored to one end of said plate, a contact normally spaced from and for coaction with said plate when said member is depressed, said contact extending through said member at the other end of the latter, means for insulating said contact from said member, and means for securing said plate to the horizontal leg, said vertical leg provided with means to permit of its being vertically adjusted relative to the support to which it is anchored. 10 15

3. In an attachment for the purpose set forth, a normally inactive circuit closing unit formed of an L-shaped supporting member having a vertical leg for anchoring to a support and a horizontal leg extending at an angle from the lower end of the vertical leg, a contact plate disposed transversely of said horizontal leg, a depressible resilient circuit closing member arranged over and having one end anchored to one end of said plate, a contact normally spaced from and for coaction with said plate when said member is depressed, said contact extending through said member at the other end of the latter, means for insulating said contact from said member, means for securing said plate to the horizontal leg, and said horizontal leg having means coacting with said securing means to provide for the adjusting 25 30 35 of said plate lengthwise of said horizontal leg. 40

4. In an attachment for the purpose set forth, a normally inactive circuit closing unit formed of an L-shaped supporting member having a vertical leg for anchoring to a support and a horizontal leg extending at an angle from the lower end of the vertical leg, a contact plate disposed transversely of said horizontal leg, a depressible resilient circuit closing member arranged over and having one end anchored to one end of said plate, a contact normally spaced from and for coaction with said plate when said member is depressed, said contact extending through said member at the other end of the latter, means for insulating said contact from said member, means for securing said plate to the horizontal leg, said vertical leg being rigid and said horizontal leg being resilient. 45 50
